UNITED STATES PATENT OFFICE.

HARRY M. NAUGLE, OF CANTON, OHIO.

METAL-LATH-ATTACHING CLIP.

1,368,742.

Specification of Letters Patent. Patented Feb. 15, 1921.

Application filed May 17, 1920. Serial No. 381,838.

To all whom it may concern:

Be it known that I, HARRY M. NAUGLE, a citizen of the United States, residing at Canton, Stark county, Ohio, have invented 5 a new and useful Metal-Lath-Attaching Clip, of which the following is a specification.

This invention relates to improvements in metal lath attaching clips and more particularly to a spring clip designed for securing 10 sheets of metal lath to steel joists.

The objects of the invention are the provision of a spring metal attaching clip which can be readily and easily applied to 15 secure the metal lath to the joist without the aid of additional securing means, to provide an attaching clip of this character which will readily adjust itself to variations in the size and shape of the joist; and 20 which will be cheap and inexpensive to manufacture and efficient in use.

The invention thus set forth in general terms is illustrated in the accompanying drawings forming part hereof, in which—

25 Figure 1 is a detail perspective view of one of the attaching clips.

Fig. 2 is a sectional view through a steel joist and a portion of a sheet of metal lath showing one of the improved attaching 30 clips partly in position upon the joist.

Fig. 3 is a sectional view through a joist and a portion of a sheet of metal lath showing the attaching clip in position thereon, securing the lath to the joist.

35 Fig. 4 is a similar view showing the position the clip assumes where the flanges of the joist are slightly narrower than normal.

Fig. 5 is a similar view showing the position the clip assumes where one flange of 40 the joist is shorter than the other.

Fig. 6 is a plan view on a reduced scale of a portion of a sheet of metal lath showing portions of two joists and the attaching clips secured thereto.

45 A practical embodiment of the invention is disclosed in the accompanying drawings, forming a part of this specification in which similar numerals of reference indicate corresponding parts throughout the several 50 views.

The invention is especially adapted for use in connection with steel joists and for that purpose the application of the clip to a joist of this character, showing the means

for connecting metal lath to the joist is 55 illustrated in the accompanying drawings.

The particular type of joist for which the clip is designed is formed of two channel members spot welded or otherwise connected together and comprises the web 1 and 60 the upper and lower flanges 2 and 3, the outer edge of each flange being bent inwardly substantially parallel with the web forming a short flange 4.

In forming the channel members from 65 which the joist is formed the metal strip from which each channel member is made may be accidentally placed at one side of the center, thus causing one of the flanges 4 to be slightly shorter than the other. 70

In order to form an attaching means which will readily adapt itself to these 75 variations in the height of the flanges 4 the present attaching clip is designed, this clip being so constructed that it will automatically adapt itself to these variations in the construction of the joist, holding the metal lath tightly in engagement with the joist.

The metal lath shown at 5 may be of any 80 usual and well known construction and is placed against the flat face of the upper or lower flange 2 or 3 respectively of the joist in the usual manner, the clip being placed in position upon the lath and extended therethrough and attached to the flanges of 85 the joist.

The clip which is indicated generally by the numeral 6 is preferably formed of spring steel and may be formed of a flat strip as shown or of spring wire bent into the shape 90 shown in the drawings. The clip comprises the arcuate body portion 7 extending the entire length of the clip and provided at its ends with the downwardly disposed legs 8 provided with inturned hooks 9 at their extremities. The normal relative position of the several portions of the clip is best illustrated in Fig. 1.

Although in the normal position of the clip, when detached, as shown in Fig. 1, the 100 legs 8 diverge slightly away from the body portion 6 of the clip, the position of the legs with reference to each other is caused by the curvature of the body portion. Each leg of the clip is located at a little less than a right 105 angle (80° to 85°) to a line tangent with the body portion of the clip at the junction of the leg and the body portion. With this

construction it will be evident that when the body portion of the clip is flexed the legs will converge slightly thus having a tendency to tightly hug the flanges 4 of the joist.

- 5 In attaching the metal lath to a joist by means of the attaching clip the lath is first placed against the flat face of the flange of the joist to which it is to be attached and one leg of the clip is inserted through an 10 opening in the lath and the hook thereon engaged with the edge of the adjacent flange 4 of the joist as shown in Fig. 2, the body portion of the clip thus extending away from the joist at an angle as shown in said figure. 15 The other end of the clip is then pressed down, the leg thereon being inserted through the lath and the hook 9 thereon engaging the adjacent flange 4 of the joist.

If the joist is of normal construction, that 20 is, if both of the flanges 4 to which the clip is attached are of normal height the clip will assume substantially the position shown in Fig. 3 of the drawings, the body portion 7 thereof being flexed into substantially a 25 straight line engaging the metal lath across the entire width of the joist and holding the same firmly in contact with the flat face of the upper flange of the joist. The legs 8 of the clip will, owing to the construction above 30 described, and due to the spring action of the clip, tightly hug the sides of the flanges 4, holding the hooks 9 firmly in position and preventing displacement thereof. Plaster 10 may then be applied in the usual manner, 35 sealing the clip to the lath and joist and forming a permanent joint therebetween.

Should both of the flanges 4, which are engaged by the clip be of less than normal 40 height, the clip will assume substantially the position illustrated in Fig. 4, the body portion thereof being slightly arcuate and engaging the metal lath at approximately the center of the joist holding the lath tightly in engagement with the joist at this point, 45 the spring in the body portion of the clip holding the hooks 9 tightly in engagement with the flange 4 of the joist.

Should one of the flanges 4 be of less 50 height than the other, as indicated at "A" in Fig. 5 the clip will assume substantially the position illustrated in Fig. 5, the body portion of the clip engaging the lath for substantially half of the width of the joist and then extending slightly away from the lath 55 at an angle, as shown at B in Fig. 5, the spring in the body portion of the clip causing the clip to be held in tight engagement with the lath for a portion of its length and causing the hooks 9 to tightly engage the 60 flanges 4 of the joist, thus holding the metal lath firmly against the joist.

It will be evident from the foregoing that 65 an attaching spring clip is provided which may be easily and readily applied to steel joists for the purpose of attaching metal

lath thereto and which will firmly hold the lath in engagement with the joist under all ordinary or practical conditions, the clip automatically adapting itself to compensate for variations in the flanges of the joist, and 70 the parts are preferably so proportioned and arranged that the length of the body portion is substantially equal to the width of the joist flange and with the relation of the parts when the body portion is deflected or 75 flexed from its normal arcuate form to be substantially straight and parallel with the face of the joist flange, the legs will be sprung outward to be substantially perpendicular to the body portion so as to clamp 80 the vertical flanges or edge portions of the joist, such being the preferable relation of the parts as shown in Fig. 3.

I claim:

1. The combination of a joist having 85 flanges presenting a flat face, expanded metal lath or the like abutting the flat face, and a spring metal clip comprising an arcuate body flattened by flexing against the lath, legs on the ends of the body inserted 90 through openings in the lath, and hooks on the legs engaged with the flanges of the joist.

2. The combination of a joist having flanges presenting a flat face, expanded metal lath or the like abutting the flat face, 95 and a spring metal clip comprising an arcuate body flattened by flexing against the lath, legs on the ends of the body inserted through openings in the lath, and hooks on the legs in springing engagement with the 100 flanges of the joist.

3. A spring metal clip for fastening metal lath or the like to a flange joist having a flat face, comprising an arcuate body with legs on the ends insertible through openings 105 in the lath and having hooks for engaging the joist flanges when the body of the clip is flexed to flatten against the metal lath.

4. A spring metal attaching clip for fastening metal lath to a flanged joist, comprising an arcuate body portion of a length substantially the width of the joist, downwardly disposed legs at the extremities of the body portion insertible through openings in the metal lath and inturned hooks at the 110 extremities of the legs adapted to engage the flanges upon the joist, said body portion being adapted to be substantially flattened when it is flexed against the lath.

5. A spring metal clip for fastening metal 120 lath or the like to a flanged joist having a flat face, comprising an arcuate body with legs on the ends insertible through openings in the lath, each leg located at an acute angle to a line tangent to the arcuate body 125 portion at the junction of the leg and body, and hooks upon the legs for engaging the joist flanges when the body of the clip is flexed against the metal lath.

6. A spring metal clip for fastening metal 130

lath or the like to a flanged joist having a flat face, comprising an arcuate body portion of a length substantially the width of the joist flange, legs on the ends of the body portion insertible through openings in the lath, each leg located at an acute angle to a line tangent to the arcuate body portion

at the junction of the leg and body and in-turned hooks upon the legs for engaging the joist flange when the body of the clip is flexed against the metal lath.

In testimony that I claim the above, I have hereunto subscribed my name.

HARRY M. NAUGLE.
